United States Patent Office

Des. 177,317
Patented Apr. 3, 1956

177,317

GAS SPACE HEATER

Roy A. Dudley, North Kenova, Ohio

Application September 21, 1955, Serial No. 38,015

Term of patent 7 years

(Cl. D81—10)

Fig. 2.

Fig. 1.

Figs. 1, 2 and 3 are front elevation, side elevation and top plan views of a gas space heater embodying my design.

The essential features of my design reside in the portions shown in full lines.

I claim:

The ornamental design for a gas space heater, as shown and described.
